ROBERT L. MEAUX, OF EUNICE, LOUISIANA

CYLINDER-BORE POLISHING AND FINISHING ATTACHMENT

Application filed November 12, 1927. Serial No. 232,865.

The present invention is concerned with the provision of a machine tool attachment for finishing and polishing any cylinder bore after the latter has been bored with the rack 5 boring tool. The attachment is intended for use on a lathe boring machine, or a portable boring bar.

An object of the invention is to provide a device of this character which will permit cylinder bores to be finished and polished with absolute accuracy, and without the production of any chatter marks and scores, such as are present in cylinders finished by a scraping tool. By producing an absolutely smooth 15 finish on the cylinder bore, many inconveniences and disadvantages are eliminated in so far as future operation of an engine is concerned. It is well recognized that cylinder bores which are scored or scraped quickly 20 produce loose packing rings and consequently loss of fuel and efficiency.

Another object of the invention is to provide a tool which is readily capable of adjustment for operation on cylinder bores of 25 different sizes.

Further objects are to provide a machine tool attachment of the character stated which will be simple and practical in construction, rugged, durable and efficient in use, and well suited to the requirements of economical 30 manufacture.

With the above noted and other objects in view, the invention consists in certain novel 35 features of construction and combinations and arrangements of parts, as will be more fully hereinafter set forth and pointed out in the claims. The invention may be more 40 fully understood from the following description in connection with the accompanying drawings, wherein—

Fig. 1 is a view mainly in end elevation of my improved polishing and finishing tool, parts of the tool being broken away and in 45 section to disclose the adjusting means, this

view being taken approximately on the line 1—1 of Fig. 2.

Fig. 2 is a view partly in side elevation and partly in longitudinal section through the 50 tool.

Fig. 3 is a side elevational view of the tool illustrating a slight modification.

Fig. 4 is a view mainly in end elevation illustrating a further modified type of tool.

Fig. 5 is a view partly in side elevation 55 and partly in section of the tool of Fig. 4.

Fig. 6 is an enlarged view partly in section and partly in side elevation of the tool of Fig. 4.

Referring first to Figs. 1 and 2 of the drawings, numeral 10 designates a boring bar, and numeral 11 designates a body in the nature of a casting keyed as at 12 to the bar, and selectively locked against movement relatively to the bar by a set screw 13. It will be obvious 60 that the body 11 may be either fixed to the bar or slidably therealong as desired.

The body includes a plurality—preferably four—radial extensions 14 presenting inclined faces 15 which converge toward the 70 forward end of the tool. The extensions 14 are preferably connected to each other by integral web portions 16 and 17 at their larger and smaller ends respectively.

The inclined faces 15 of the extensions 14 75 are machined to provide tracks and formed with longitudinally extending T-grooves 18 therein receiving T-bolts 19 carried by carriage blocks 20 which move on the tracks. The carriage blocks 20 may be secured against 80 sliding movement along the tracks by tightening nuts 21 associated with the T-bolts.

Each of the carriage blocks is provided with a recess 22 in its outer face receiving a hone 23. The hones are backed by plates 85 24, the latter being spring pressed outwardly by coiled expansion springs 25 arranged in pockets 26 in the carriages 20; these pockets communicating with the bottoms of the hone-receiving grooves 22.

Retainer strips, such as strips 27 are secured to the end faces of the carriage blocks 20 and engage the projecting ends of the plates 24 to limit outward movement of the latter.

Projecting laterally from one side of each carriage block are pairs of web-like extensions 30, these extensions being spaced apart for the reception of movable carriage operating plates 33. The plate 33 at each end is formed with pins 32 received in open slots 31 formed in the webs 30.

The plate 33 is mounted upon an operating screw 35 rotatably journaled at each end in the web 16 and 17 and having a projecting squared end 36 for the reception of an operating key.

As the screw 35 is turned, plate 33 is fed along the screw, carrying with it two of the carriage blocks 20. The connection afforded by the pins 32 and slots 31 is such, that relative separation of the two operated carriage blocks as they move toward the high ends of their slides, is automatically accommodated for.

As best seen in Fig. 1, I use two screws 35 for operating the four blocks, a single screw serving, due to the construction above described, to adjust two blocks simultaneously along their inclined tracks. This adjustment of course moves the blocks radially in and out relatively to the shaft 10, and permits ready adjustment of the tool for polishing and finishing cylinder bores of different sizes.

The construction shown in Fig. 3 is in all respects similar to that illustrated in Fig. 2, except that the blocks 20 instead of being directly keyed into the tracks, are spaced further from the central shaft 10 by skeleton webs 20^a, these webs being keyed to the tracks.

The form of the invention shown in Figs. 4 and 5 involves the use of a generally similar construction, except that the inclined tracks are eliminated, and the hone carriage blocks are adjusted in and out by the use of shims 40.

In Fig. 6, raising blocks 41 are substituted for the shims.

All forms of the invention provide some means for effecting radial adjustment of the hones relatively to the central tool carrier shaft 10. All forms of the invention contemplate the use of a key and set screw, such as shown in Fig. 1, for retaining the tool against longitudinal movement relatively to its shaft 10, or the use of a key and a groove 12^a such as shown in Fig. 6, which permits sliding of the tool along the shaft 10. In all forms of the invention, the tool is keyed to turn with the shaft. It is believed that the operation of the device when the tool is attached to a lathe boring machine or a portable boring bar, will be obvious from the foregoing description. The use of the spring pressed hones instead of cutters prevents tool marks or chatter marks in the finished cylinders,

and leaves the cylinder absolutely devoid of roughness at any point.

Obviously, various changes and alterations might be made in the general form and arrangement of the parts described without departing from the invention. Hence I do not wish to limit myself to the details set forth, but shall consider myself at liberty to make such changes and alterations as fairly fall within the spirit and scope of the appended claims.

I claim:

1. A machine tool attachment for finishing cylinder bores, including a body keyed to an operating shaft, a plurality of carriage blocks mounted on the body and radially adjustable relatively to the longitudinal axis of the shaft, hones mounted on the carriage blocks, and springs urging the hones outwardly into engagement with a surface to be finished, said body including radial extensions having inclined outer faces along which the carriage blocks are slid able, the blocks being keyed to the extensions for sliding movement along the inclined faces thereof.

2. A machine tool attachment for finishing cylinder bores, including a body keyed to an operating shaft, a plurality of carriage blocks mounted on the body and radially adjustable relatively to the longitudinal axis of the shaft, hones mounted on the carriage blocks, and springs urging the hones outwardly into engagement with a surface to be finished, said body including radial extensions having inclined outer faces along which the carriage blocks are slid able, the blocks being keyed to the extensions for sliding movement along the inclined faces thereof, and manipulating screws for sliding the blocks.

3. A machine tool attachment for finishing cylinder bores, including a body keyed to an operating shaft, a plurality of carriage blocks mounted on the body and radially adjustable relatively to the longitudinal axis of the shaft, hones mounted on the carriage blocks and springs urging the hones outwardly into engagement with a surface to be finished, the body including inclined outer faces along which the carriage blocks are slid able, screws rotatably mounted in the body, operating plates working on the screws, the carriage blocks including forked extensions, the arms of which receive the operating plates.

4. A machine tool attachment for finishing cylinder bores, including a body keyed to an operating shaft, a plurality of carriage blocks mounted on the body and radially adjustable relatively to the longitudinal axis of the shaft, hones mounted on the carriage blocks, and springs urging the hones outwardly into engagement with a surface to be finished, the body including inclined outer faces along which the carriage blocks are slid able, screws rotatably mounted in the body, operating plates working on the screws, the carriage
